UNITED STATES PATENT OFFICE.

JOSEPH H. TEMPLIN, OF PHILADELPHIA, PENNSYLVANIA.

PORTABLE VACUUM-PUMP.

956,784.

Specification of Letters Patent.

Patented May 3, 1910.

Application filed November 13, 1909. Serial No. 527,924.

To all whom it may concern:

Be it known that I, JOSEPH H. TEMPLIN, a citizen of the United States, residing at Philadelphia, in the county of Philadelphia 5 and State of Pennsylvania, have invented certain new and useful Improvements in Portable Vacuum-Pumps, of which the following is a specification.

My invention relates to portable vacuum pumps of various modified types adapted to be used for the well known method of vacuum cleaning. Heretofore vacuum pumps of this type were located in a distinct and separate or partitioned off chamber from the 15 vacuum or dust separating compartment or chamber.

In my improved construction the vacuum chamber forms part of the pump construction there being no partition, orifices, or air 20 passages between the vacuum chamber and the pumping mechanism, the casing which covers the pump forms the only chamber or compartment which wholly surrounds the mechanism of the pumps. The air as it is 25 exhausted from the chamber causes an inrush of air into the inlet and as the free air rushes into the vacuum chamber it circulates freely around the pumping or exhausting mechanism and the motors driving same, thereby cooling off same, before entering 30 into the pumping mechanism, through same and out into the open air.

The object therefore of my invention is to 35 reduce the number of parts and simplify same, cheapen the cost of construction, reduce the weight, increase the efficiency, and make a truly portable and noiseless machine of this character.

In the accompanying drawings Figure 1 40 is a vertical section of my apparatus showing a double acting diaphragm pump used as an exhauster for producing a vacuum. Fig. 2, is a similar view showing a double bellows. Fig. 3 is a similar view showing 45 an exhaust fan. Fig. 4 is a similar view showing a three stage turbine.

Similar numerals of reference indicate like parts throughout the different views.

Referring to the drawings 1 is the main 50 casing forming a vacuum chamber 2, and completely surrounding the pumping devices. Gaskets 3 and 4 interposed between casing 1 and cover 5 also between casing 1 and base 6 clamped together respectively by 55 any well known clamping means form a hermetically sealed chamber 2. Base 6 forms a

support for the pumping mechanism and as shown in Figs. 1 and 2 is provided with an exhaust port 7 (used for blowing purposes when desired) leading direct from the pump.

In Figs. 3 and 4 the exhaust is taken through the side of the casing at 8 when the pumping mechanisms are disposed as shown. When they are inverted as in Figs. 1 and 2 the exhaust would be of course transmitted through the base at 7 as shown in Figs. 1 and 2. Cover 5 is provided with an outlet 9 into which the dust-laden air passes through the well known medium of suction 7 hose and renovator, not shown.

10 is a dust separator supported within the vacuum chamber 2.

11 is an auxiliary separator or plate screen of fine material, said plate 11 is disposed loosely on the support 12 in casing 1. It is easily removable and is optional whether same is used or not.

In Fig. 2, I have shown a novel joint whereby noise, friction and necessity of lubrication are eliminated. Connecting rod 13 is pivotally connected to crank pin 14, the opposite end of the connecting rod is provided with a yoke 15, said yoke spanning lugs 16 freely and terminates in flanges 17. 18 and 18 are another pair of lugs on connecting plate 19.

Between lugs 16 and 18 is firmly clamped and supported a resilient strip 20 of metal or rawhide. Flanges 17 on yoke 15 are also firmly clamped to said strip 20.

By the above device the upper end of the connecting rod can vibrate with the crank pin and the lower end can "give" accordingly without friction or lubrication and is noiseless.

The operation of the mechanism is readily seen. The dust laden air passes into inlet 9 down through separator 10 which retains the dust therein through auxiliary screen 11 thence passing freely around the motors 21 cooling same, thence into the inlets 22 passing through the inlet and outlet valves respectively and thence out of the exhaust port 23 into the open air.

In the above system while I have shown my preferred types I do not wish to limit myself to same or to the exact construction in all details of same, as numerous modifications of same can be made by those skilled in the art and still come within the scope of my invention, as instead of a double

acting compressible vacuum producer, pistons may be employed, or instead of a double acting, a single acting mechanism may be employed or as stated before the turbine and fan mechanisms could be inverted or the double acting pump could be inverted from its present position and the purpose and operation still remain within one casing or vacuum chamber covering the whole mechanism, said mechanism all operating in a vacuum element.

Having thus described my invention what I claim as new and desire to secure by Letters Patent is:—

1. As an improved article of manufacture, a casing having a bottom or base, said base provided with an outlet, a cover for said casing provided with an inlet, said cover removably attached and sealable to said casing thereby forming a vacuum chamber, vacuum producing means secured to said bottom or base, a motor operatively connected with said vacuum producing means, said motor and said vacuum producing means being located wholly within said vacuum chamber, and furthermore said vacuum producing means and said motor being wholly secured to said bottom or base and having no contact whatsoever with the side-walls or top of said vacuum chamber, all in combination as and for the purpose set forth.

2. As an improved article of manufacture, a casing having a detachable cover and base forming a vacuum chamber, in combination with vacuum producing means, means for driving said vacuum producing means, said driving means and said vacuum producing means being located wholly within said vacuum chamber and secured to said vacuum-chamber-base, whereby said means can be removed as a whole from said vacuum chamber.

3. A vacuum-chamber-casing, a detachable cover for said casing provided with an inlet, a detachable base for said casing provided with an outlet, vacuum producing means secured to said base, a motor operatively connected to said vacuum producing means, said motor and said vacuum producing means being wholly located within said vacuum chamber, all in combination as and for the purpose set forth.

4. As an improved article of manufacture, a casing having a bottom or base, said base provided with an outlet, a detachable and sealable cover for said casing, said elements forming a vacuum chamber, said cover provided with an inlet adapted to receive a suction hose, vacuum producing means secured to said bottom or base, a motor operatively connected with said vacuum producing means, said motor and said vacuum producing means having no contact whatsoever

with the side walls nor with the cover or top of said vacuum chamber, said vacuum producing means and said bottom or base adapted to receive a resilient packing or buffer disposed between the contact face of said vacuum producing means and the contact face of said bottom or base, to which contact face said vacuum producing means is secured, all in combination as and for the purpose set forth.

5. In a portable vacuum pump, a pump-chamber, a reciprocating displacing member or piston located in or attached to said chamber, a pair of lugs disposed on the side of said displacing member or piston mechanism, a straight flexible member disposed between said pair of lugs, one end of said member being secured to one of said lugs, the opposite end of said member being secured to the other lug, a crank-shaft provided with a crank pin, a connecting rod pivotally connected at one end with said crank pin, the opposite end of said connecting rod adapted to be clamped to the middle portion of said flexible member, said flexible member, said supporting lugs and said connecting rod being disposed longitudinally in line with each other in the direction of the travel of said displacing member, whereby a practically rigid connection longitudinally as well as a slight flexibility or resilience transversely of said flexible member is attained all in combination with means for driving said crank-shaft as and for the purpose set forth.

6. In a portable vacuum pump, a pump-chamber, a reciprocating displacing member or piston located in or attached to said pump-chamber, driving lugs 16 and 18 disposed on the side of said displacing member or piston mechanism, a flexible member 20 disposed between said lugs 16 and 18, one end of said flexible member 20 being supported by lug 16, the opposite end of said member 20 being supported by lug 18, a crank shaft provided with a crank-pin 14, a connecting rod 13 pivotally connected at one end with said crank pin 14, the opposite end 17 of said connecting rod 13 adapted to be clamped to the middle portion of said flexible member 20, said flexible member 20, said lugs 16 and 18 and said connecting rod 13 being disposed longitudinally in line with each other, in their respective positions, and in a line parallel with the direction or axis of the travel of said displacing member or piston, all in combination with means for driving said crank-shaft, as and for the purpose set forth.

In testimony whereof I affix my signature in presence of two witnesses.

JOSEPH H. TEMPLIN.
